Primary Examiner — Jennifer Rivard*Assistant Examiner* — April Rivas(74) *Attorney, Agent, or Firm* — Ronald E. Prass, Jr.; Prass LLP(57) **CLAIM**

The ornamental design for a utility bag, as shown and described.

DESCRIPTION

FIG. 1 is a front perspective view of a utility bag showing my new design in accordance with a first embodiment;

FIG. 2 is a side view thereof, the other side being a mirror image thereof;

FIG. 3 is a front view thereof;

FIG. 4 is a rear view thereof;

FIG. 5 is a top plan view thereof; and,

FIG. 6 is a front perspective view of a utility bag showing my new design in accordance with a second embodiment.

The broken lines shown in the drawings illustrate portions of the utility bag and form no part of the claimed design.
